Another part relates to the ornamentation of the front door, the same consisting of the ornamental base *d*, scroll-standard *e*, and the lateral scroll-vines *f* *f'*. Another part relates to the ornamental legs, the same consisting of the convexly-curved surface *g*, compound scroll and rosette ornament *h*, curved top edge, *i*, downwardly-converging curved side edges, *j*, contracted lower part, *k*, and rounded foot *l*.

The design for the stove-body embraces the oblong side plate having the compound ornamentation *a* *a'*, *b* *b'*, *c*, the end plate, with the swelling front door, having the ornamentation *d* *e* *f* *f'*, the top plates, and the bottom plate having the front hearth.

The whole design embraces the ornamented side plate, end plate with the ornamented

front door, top plates, bottom plate having the front hearth, and the ornamented legs.
